COKING RETORT OVEN

Joseph Becker, Pittsburgh, Pa., assignor to Kop-
pers Company, a corporation of Delaware

Application May 11, 1936, Serial No. 79,085

6 Claims. (Cl. 262—151)

The present invention comprehends improvements of general utility in the coking retort oven art; and comprehends more specifically improvements in the underfiring systems of such coking retort structures of the well-known Becker cross-over flue type as are provided with means for introducing the underfiring gases into the heating flue systems according to the well-known and so-called underjet principle. The cross-over principle of flow of the heating gases was patented in Joseph Becker U. S. Patent No. 1,374,546, granted April 21, 1921, and certain features of specific embodiments of that principle, as exemplified in Joseph Becker U. S. Patent No. 1,904,191, granted April 18, 1933, and my co-pending application Serial No. 2,564 filed January 19, 1935, relate to the instant invention and improvement, and the latter further improves upon the Joseph Becker Patent 1,704,239, issued 20 March 5, 1929, on my application filed May 29, 1925.

In coking retort oven heating systems embodying the cross-over principle of flowing the hot combustion gases from the heating flues of an oven wall to the flues of the opposite wall of the coking chamber, the heating media are introduced into the lower parts of vertically disposed flame flues and as they rise therethrough are burned. The upper ends of the flame flues 25 of the heating walls communicate with horizontally extending flow or bus ducts which also connect with flow ducts or cross-overs that extend upwards and over the tops of the coking chambers and direct the products of combustion from the burning flame flues of an oven wall into corresponding horizontal ducts and heating flues in adjacent heating walls.

The cross-over flow ducts are positioned at preferred intervals along the horizontal flow duct thereby providing a plurality of outlets for the gases of combustion from any heating wall into that opposite wall with which it is communicably connected for underfiring purposes. In general said horizontal bus channels are each divided by at least one division wall at the central longitudinal plane of the battery so that the heating gases of the flues on the pusher side of the battery do not commingle with those of the coke side, thereby providing means for 40 separately controlling the flow of gases on both such sides to meet the different gas requirements of the coke and pusher ends of the respective coke ovens. As the horizontal bus channels of the oven walls are increasingly subdivided into 45 a larger number of shorter bus channels, each

of which is supplied with its own cross-over for directing the gases of combustion from one section of an oven wall into a corresponding section in the opposite wall as exemplified in the above-mentioned Patent No. 1,904,191, the horizontal path the flowing gases are required to assume is proportionately reduced as the number of subdivisions is increased, with the result that the vertically rising gas streams in the heating flues are increasingly less deflected from their 10 normal vertical paths, thus simplifying control and regulation of the temperatures in the individual flues. Increasing the number of cross-overs provides an added advantage in that the volume of combustion products that must be carried by a single cross-over is correspondingly reduced, with a resulting decrease in the required dimensions of these cross-over ducts. This size reduction also provides the advantage 15 that the masonry at such points may be thickened and the solidity of the structure thereby 20 generally improved.

The cross-over type of construction by permitting the employment of a plurality of outlets for the combustion gases flowing from a heating wall into the adjacent one with which it is communicably connected for under-firing purposes combined with the above-mentioned subdivided horizontal bus channel, makes it possible to separate an oven heating wall into 25 individually operable and regulable zones or belts for under-firing purposes. That is to say, the coking ovens may be divided lengthwise of the chambers into a plurality of sections each having its own cross-over, and within each such section 30 preferred regulating and controlling measures may be carried on without unduly disturbing existing conditions in other sections of the same wall. This possibility of independent operation for the plurality of heating sections or zones provides a highly desirable means for obviating the 35 effects of those conditions which tend to complicate the maintenance of substantially uniform temperatures at all points of the rather extensive surface of an oven heating wall and interfere with the uniform progress of the carbonization reaction through a coal charge. Numerous 40 factors tend to interfere with the establishing of this desired uniformity of heats in the plurality of flues comprising an oven wall, as for 45 example, the higher radiation losses from the end flues of a wall and the difference in the thickness and mass of the coal charge at opposite ends of an oven.

The aforementioned possibility of segregating

the combustion products flowing through the various zones into which an oven heating wall may be divided by employing the cross-over flue type of construction, and the obvious advantages 5 that accrue from such provision, make it apparent that any refinement and improvement in the means for introducing the under-firing media into the flame flues so that such zones may be effectively regulated and independently controlled from without the battery structure and without disturbing established conditions in other 10 sections of the same wall, will furnish means tending to promote a closer approach to complete independence of such heating wall zones from each other and facilitate the maintenance of more uniform heats throughout a battery structure.

In my co-pending application S/N 2,564 filed January 19, 1935, is disclosed an improved disposition of the heating flues to form wall-groups 20 for the flow of combustion products, said groups being segregated from each other for that purpose by partition walls in the horizontal bus channel. In the therein disclosed improvement, the 25 gases of combustion flowing from the vertical heating flues into any horizontal bus channel section are provided with flue ports of such cross-sectional area as to offer no throttling or impedance to gas flow therethrough, and substantially 30 the same length of travel is also provided for all combustion products assembling in the same bus section and cross-over. All throttling or regulation of the gases flowing into the heating flues is effected at their lower parts, so that the flues 35 comprising any heating wall section are provided with gases at a substantially uniform pressure, and the pressure differential between the interior of the coking chamber and the heating flues is greatly reduced. In one embodiment of my invention therein disclosed, the underfiring gas is 40 introduced into the flame flues according to the underjet principle, and volume flow of heating gas to individual flame flues is regulated by means of valve means positioned near the lower end of 45 each of the rich gas conduits that rise through the regenerator division walls from heating wall distributing headers which also communicate with the main fuel gas supply artery. Regulation may be effected by adjustable valves or, if 50 preferred, by orifices placed at appropriate points in said distributor-headers. The relatively small openings required to establish the desired flow of gases to the heating flues may interfere with the introduction of sufficient decarbonizing air, during 55 the reversal period, to remove such quantities of carbon as may be deposited in the hot rich gas conduits of the regenerator walls by a cracking of the heavy hydrocarbon components of the underfiring gas. In order to obviate this circumstance, I provide in my present improvement 60 means whereby the gas flow regulating devices for regulating the volume of gas flow from the distributor-headers through the rich gas conduits may be by-passed by the air introduced into the down-flowing flame flues and through the rich 65 gas supply conduits during those intervals said conduits are not functioning as underfiring gas distributors.

An object of my present invention is to provide 70 an improved distributing system for flowing rich gas to the heating walls of a battery having the heating flues of its heating walls disposed in individually operative heating groups, as above-described, so that each such flue-group and its associated oven-wall zone isolated for the under-

firing purposes, may be independently regulated and controlled without disturbing established regulations and conditions in the other zones of the same heating wall, and all flues comprising each such group be assured of a rich gas supply at a 5 substantially uniform pressure.

A special object of my invention is the provision of a decarbonizing arrangement especially adapted to the rich gas distribution system of my invention and disposed for actuation by the reversing mechanism.

Another object of my invention is to furnish, for the rich gas distribution system of my present invention, regulatory means that are easily accessible from the basement of the battery structure so that the flow of rich gas into the different heating-wall sections of a battery may be adjusted extraneously of the flues, said system containing a device assuring a uniform volume of rich gas being delivered into the flame flues of 20 any wall section from that distribution system.

A further object of my invention is the provision of simple and effective means whereby the necessity of employing graduated orifices in the under-jet pipes for the individual flame flues will 25 be eliminated, said means being designed and adapted to permit the flowing of decarbonizing air into the rich gas distributing conduits of an under-jet oven without its ingress being restricted by the rich gas flow regulating means, so that 30 an excess of air can be conveniently introduced into these conduits for the burning out of carbon deposits during that interval of the reversing cycle said conduits are not operating to distribute underfiring gas.

The invention has for further objects such other improvements and such other operative advantages or results as may be found to obtain in the processes or apparatus hereinafter described or claimed.

According to the preferred embodiment of my improvement, I provide for coke-oven batteries, equipped for underfiring according to the underjet principle, a rich gas distribution system comprising branch mains that communicate with a 45 main rich gas supplying-main and extend along the ceiling of the battery basement crosswise of the oven chambers, each of the similar and similarly positioned and individually operative heating flue groups into which the heating walls 50 of a battery may be divided by employing the cross-over type of construction, being communicably connected with the same, or functionally the same, branch main or header positioned beneath the battery supporting mat and substantially along the central crosswise plane of the therewith associated heating-wall zones. Between each branch-header and each of the corresponding multiplicity of separately regulable heating-flue groups, I dispose a gas pressure 55 equalizing-duct or bus channel, which communicates at its lower part with the above-mentioned branch-header, and at its upper part with vertically rising gas ducts that extend through the regenerator division walls to the base of the vertically disposed heating flues comprising the heating zone. These pressure equalizing bus channels may be variously positioned between the branch-headers and the rich gas flue ports without departing from the purpose and spirit of my 70 invention, i. e. the bus channel may be outside the battery masonry and adjacent the branch distributing headers or within the brick-work of the battery and close to the lower parts of the heating flues, as will be hereinafter disclosed. My 75

invention also provides valve and valve-reversing means for regulating the flow of rich gas in my improved distribution system and a novel method of introducing the decarbonizing air into the under-jet distributor ducts.

In the accompanying drawings forming a part of this specification and showing for purposes of exemplification a preferred apparatus and method in which the invention may be embodied and practised but without limiting the claimed invention specifically to such illustrative instance or instances:

Figure 1 is a composite vertical section transversely of a battery built according to my present invention; the section to the left being taken through the heating flues and that to the right through the coking chamber;

Figure 2 is a fragmentary vertical section longitudinally of the battery on the line II—II of Figure 1.

Figure 3 is a vertical section of a battery taken longitudinally through the heating wall along the line III—III of Figure 4 and showing another method of embodying the principle of my invention;

Figure 4 is a vertical section along the line IV—IV of Figure 3;

Figure 5 is an enlarged view of one of the gas valves and one of the decarbonizing devices employed to respectively introduce the underfiring gas and decarbonizing air into the gas pressure equalizers of my invention;

Figure 6 shows an alternative embodiment of my invention and a disposition of the pressure equalizers in respect of a heating-gas distributor-header, which permits an entire oven wall being supplied with heating gas from the same distributor;

Figure 7 is an enlarged view along the line VII—VII of Figure 6 showing a means of introducing the decarbonizing air into the rich gas conduits of underjet ovens according to my improved method.

Referring now to Figure 1 showing a preferred embodiment of my invention, the coking chamber 10 is one of any preferred number of horizontal oven chambers lying side-by-side and alternately disposed between the heating walls 11 to form a battery of the same. The opposite ends of each oven are closed during the coking period by means of removable doors 12, and the coal to be carbonized is charged into the oven through charging-holes 13 provided in the top of the battery for this purpose. The heating walls 11 are maintained at the desired temperature for effecting the distillation of the coal charge by burning, within the flame flues 14, rich gas flowed through the distributing branch-headers 15, the regulating valve means 16, the equalizing bus channel 17 and the rich gas conduits 18 positioned in the walls 19 which separate, from each other, the side-by-side heating wall cross regenerators 20 that extend transversely of the battery its entire length. The rich under-firing gas rising under slight pressure through the conduits 18 flows into the up-burning flame flues 14 through the removable port-determining nozzles 21. At the lower part of the flame flues, the rich gas is mixed with the combustion air drawn through the air ports 22 by the draft induced by the stack with which the under-firing system of the battery communicates in the well-known manner. Said combustion air, following its introduction into the regenerator sole-flues 23, is distributed through the regenerator space

20 by means of the sole-flue ducts 24. In the regenerators, the combustion air is pre-heated and distributed to the individual flame flues through the conduits 25 and the ports 26 situated at their upper ends. The pre-heated gas and air burn in the flues 14 and evolve heat which is conducted through the chamber walls 11 to the coal charge. The products of the combustion reaction rise through the flame flues and assemble in the horizontal bus channels 27 and flow upward through the cross-overs 28 over the tops of the ovens and into the corresponding flame flues in the opposite heating walls of the oven chambers. At preferred intervals the flow of gases in the battery under-firing system is reversed and the up-burning flame flues become the down-flowing ones upon reversal of the regenerative system. This reversal of flow is effected by proper adjustments on the valves 16 and the air-flow boxes (not shown) controlling the volumes of air entering the regenerator sole-channels 23.

As will be noted the heating flues 14 comprising each heating wall and which, in the present embodiment of my invention, all operate simultaneously either as up-flowing or down-flowing flame flues, are disposed into groups or sets of four for gas-flow purposes, with the exception of the two flues at both ends of a coking chamber which are disposed in pairs, by means of the partition walls 29, which separate the horizontal bus channel 27 into a plurality of shorter channels, each provided with its own cross-over. In this manner the plurality of vertically disposed heating flues along the wall of an oven is divided into a series of individually operable and regulable heating flue-groups, adjacent the oven charge, which are individually adjustable to permit establishing zones or belts of heating in which thermal units may be liberated in correspondence with the different heat requirements of the divers quantities of coal found at various points along the oven chambers from the coke-side to the pusher-side, and in which the different heat losses by radiation from said groups, in consequence of their different remotenesses from points of average radiation losses, may be compensated for.

It will be also noted that the alternate flue-walls of each group of four flues are flared at their upper terminals to provide flue ports, for porting into the horizontal bus channel, which are of sufficient cross-sectional area in relation to the flue cross-sectional area to offer no significant obstacle to gas flow, and to establish a substantially equal flow-path for all the gases of said flue-group in their transit through the vertical flues and horizontal flow duct to the communicably connected cross-over.

It is a well-known fact that the total pressure exerted by gases flowing through a conduit therefore comprises two components, the velocity and the static pressure. In a conduit closed at one end and provided with lateral off-takes for the gases, the total gas pressure remains the same along the length of the conduit but the component pressures vary, i. e. as the distance from the gas-supplying end increases, the velocity head diminishes and the static head increases. The static head is that which causes the gases to flow from the provided lateral orifices, and if these orifices are all of uniform size it is obvious that increasingly larger volumes of gas will be discharged therefrom as their distances from the inlet end of the conduit is increased.

It is furthermore obvious in consequence of

this fact that the heretofore common practice in the art of introducing the under-firing gas into all the heating flues comprising each heating wall from a single distributing header for that wall, extending cross-wise of the battery and communicating at its one end with a single main rich gas supplying main, has required individual valve means for each flue connected therewith so that the differences in static pressure in the single distributor-header beneath each flue, may be compensated for to the end of obtaining preferred temperatures in the various flues along the wall.

By means of my improvement, in which I divide the heating flues of a heating wall into a plurality of flue groups independently operable for gas flow purposes, and interpose a pressure equalizing bus channel between the distributor-header and the rich gas conduits of the flues of each group, the influence of the above-mentioned changes in static pressure can be substantially reduced since any one of the rich gas conduits of the battery is a comparatively short distance removed from the gas inlet port of an equalizing header and the small number of rich gas conduits leading therefrom will consequently carry rich gas at substantially uniform static pressure. My invention also makes possible a significant reduction in the number of valve means required to give the preferred rich gas distribution to the heating walls of a battery.

Referring again to Figure 1, the branch-headers 15, extending longitudinally of the battery and connected with a gas-main that communicates with the rich gas supply reservoir, are provided with vertically extending riser pipe connections 30 at intervals, along their lengthwise dimension, corresponding to the centre-to-centre distance between the opposite heating flues of an oven. The pipes 30 port into the equalizing busses 17 at about their central point, and the four rich gas conduits 18, segregated by means of the horizontal bus channel division walls 29, and adapted to supply heating gas to the four heating flues comprising a heating flue group, are disposed pair-wise on each side of the junction of pipe 30 with its equalizer 17.

Due to the static pressure equalizing effect of the equalizer bus 17, gas entering said bus from the distributor-header 15 through the valve means 16, will rise through the communicably connected conduits 18 of any one flue group at substantially uniform static pressure irrespective of the static pressure obtaining in said distributor-header up-stream of the valve 16, or its relative position or remoteness from the main gas supply line for the battery. Not only does my invention provide for a uniform flow of underfiring gas to the heating flues of any one flue group but it also furnishes means whereby all correspondingly positioned flue groups of a battery, which have substantially the same heat requirements in consequence of similar opportunities for radiation and equivalent masses of coal adjacent thereto for coking, may be supplied with underfiring gas from the same distributor-header 15. Such disposition of the distributor-headers makes it possible to raise or lower the temperature in any particular oven wall zone or in all similarly positioned oven wall zones of a battery without disturbing or altering satisfactorily established temperatures in other flue groups of the battery. For example, the volumes of underfiring gas flowing to the end flues of a battery's walls may be simply and effectively al-

tered to compensate for the different amounts of radiation therefrom at different seasons of the year without altering combustion conditions existing in other zones of the battery heating walls.

This preferred embodiment of my invention, in which a preferred regulation of the underfiring gas flowing to a group of heating flues can be effected by only one valve means, permits employing comparatively larger apertures therein, with the result that they show less tendency to precipitate adventitious materials of the gas and develop obstructions tending to reduce the volume of gas flowing therethrough. The precision of valve adjustment demanded in the case where one valve aperture regulates the flow of underfiring gas to a plurality of flues is not so great as in those instances having individual valve means for each flue, since, in the former instance, any irregularities in the volume of gas flowing through the valve means will be distributed over a plurality of flues instead of into a single flue and in consequence my system serves as a significant protection against the danger of fluxing the heating flues by any irregularities of heating gas distribution.

Furthermore, my invention, by providing means for distributing fuel gas into the heating flues of a heating wall according to the requirements of the different sections of the wall, eliminates the tedious and expensive operation of graduating and setting the gas port nozzles to effect the same end. In my system, therefore, the nozzles 26 at the base of the flues may all have apertures of the same dimension.

A special feature of the above-described specific form of my invention is that the pressure equalizing bus channel 17 eliminates the need of individual means for regulating the flow of gas to each of the vertical rich gas conduits 18. Gases flowed through the valve 16 will be substantially uniformly distributed to all heating flues communicating therewith and without further regulating means being required, with the result that these conduits are unobstructed throughout their entire length by any restrictions and are capable of carrying significantly larger volumes of gases than are ordinarily required for heating purposes.

In consequence of these facts my system offers improved advantages for the decarbonizing process. The substantial and unobstructed cross-sectional area of the conduits 18 makes it possible to introduce therein larger quantities of air for burning out any carbon deposited by the cracking of the heating gas flowing therethrough than is the case where restrictions are required in each conduit to effect the desired regulation of the heating gas.

As a further feature of my invention, I may vary the pressure at which the fuel gas is supplied to corresponding heating flue groups of a coking structure by inserting valve means between the main rich gas supply main and the various therewith communicating branch headers 15 as at some point as A in Figure 2.

As hereinbefore mentioned, the gas pressure equalizing channels for the flue groups into which the heating flues of an oven wall may be divided for gas flow purposes so that each heating wall is divided into a plurality of separately operable and regulable heating zones, may be provided outside the battery brickwork as hereinabove described, but may be also contained within the brickwork of the battery structure.

Referring now to Figures 3 and 4 such an al-

ternative embodiment of my instant invention is shown. In this specific form, the pressure equalizing channels, for any wall, take the form of a discontinuous horizontal channel located in the brickwork in the tops of the pillar walls 43. Each section 40, into which such discontinuous horizontal channel in partitioned forms a gas pressure equalizing channel for each of the flue groups into which a heating wall is divided. For each heating flue of a group thereof, a short vertical duct 41 extends from its channel 40 into the base of the flue. The distributor-headers 15 are each connected with a channel 40 by means of single vertical duct 42 extending upward through an oven pillar wall. My improvement, when so embodied, provides an important reduction in the number of vertical ducts required to be provided in the pillar walls, thereby increasing the integrity and solidity of said walls in a structure incorporating the underjet underfiring principle and decreasing the opportunity for the development of gas leaks into the regenerators from said conduits. An added advantage in this form of my invention is that fewer conduits 25 need be maintained in gas-tight condition.

My invention as hereinabove disclosed, and illustrated by specific forms it may assume to realize the advantages thereby offered, also lends itself especially to a practical simplification and improvement in the method and means employed to introduce decarbonizing air into those channels carrying fuel gases, at elevated temperatures and under non-oxidizing conditions, to the flame flues of a coking retort battery structure 35 according to the underjet principle.

It is well known that gases of relatively high calorific value, when flowed through channels maintained at elevated temperatures, suffer a certain degree of pyrogenetic decomposition, 40 more especially of the complex higher molecular weight components thereof, to deposit in such channels quantities of carbon which must be removed lest the available cross-sectional area of said channels for gas flow become increasingly 45 reduced.

It has heretofore been a common practice to distribute the heating gas to the up-burning flame flues of an oven heating wall of an underjet battery through a branch-header paralleling said wall and located in the battery basement. Fuel gas was flowed into said branch-header by means of a reversing valve located at the junction of the branch-header with its main fuel gas supply line. The preferred quantity of fuel gas was distributed to each up-burning flame flue through a metal orifice positioned in the riser pipes and individually connecting each such flame flue with the branch-header. The reversing cock was of the three-way type and so disposed as to admit 55 decarbonizing air into the branch-header during those intervals any flame flues were functioning as down-flowing flues, said air being drawn into the branch-header at the reversing cock by the stack draft. This arrangement required that all 60 decarbonizing air for burning out carbon deposited in the rich gas conduits within the regenerator walls, was of necessity distributed through the afore-mentioned gas regulating orifices. Such orifices were relatively small and 65 the quantity of air reaching the rich gas conduits for this purpose was limited by the size of the orifices required to deliver the preferred quantities of fuel gas to the flame flues. It will be appreciated that as the heating value of a fuel 70 gas increases, less gas will be required to pro-

duce the preferred temperatures in the heating flues; and other things being equal, the area of the apertures in the flow regulating orifices will of necessity be reduced. It is well-known that fuel gases of the higher calorific values contain 5 higher proportions of carbon compounds having a complex structure than fuel gases of lower heating value, and that such compounds are more sensitive to disruption by high temperatures to deposit elemental carbon. As a result therefore, for those underfiring gases most inclined to yield relatively more deposition of carbon in the distributing conduits, smaller orifices are required for their preferred regulation. This situation has the effect of decreasing the amount of 10 air that can be made available to the underfiring system, for the purpose of burning out said carbon deposits, when it is highly desirable that such 15 quantity be increased.

My instant invention which provides gas pressure equalizing channels between the distributor-header and the group of heating flues provided with fuel gas thereby, so that the heating flues, comprising any group thereof, may all be supplied with heating gas at substantially uniform 20 pressures by employing only one valve means for each flue group, adapts itself especially to an improved method of introducing decarbonizing air 25 into the flame flue rich gas conduits in a manner to obviate the above-described limitation of air 30 ingress.

My improved method and means of introducing decarbonizing air into an underjet oven comprised providing, in the vertical riser connecting a distributor-header with a group of heating flues, a port means positioned down-stream of heating gas regulating means, which can be intermittently opened or closed to respectively allow air to flow into the underfiring system from the atmosphere or to interrupt such flow. By referring to Figures 40 6 and 7, the advantages resulting from locating the decarbonizing air port in the above-mentioned position will be more obvious. It should be mentioned at this point that Figure 6 shows a form of my invention somewhat modified from the embodiment thereof shown in Figure 1. In the Figure 6, I have oriented the distributor-headers that extend from the main rich gas supplying main in such manner that they extend substantially parallel with the heating walls, and between said headers and the heating flue groups into which the oven wall is divided, I have placed the gas pressure equalizing channels that supply the individual flue groups. The result is that I supply the plurality of flue groups of any one heating wall with heating gas from the same distributor-header instead of, as shown in the modification in Figure 1, supplying all the similarly positioned flue groups of a battery from the same header. This alternative embodiment of my improvement occasions the same practical results as the preferred form thereof and does not depart from the spirit and intent of that improvement.

Figure 6 shows in schematic diagram this alternative means of exploiting my improvement and Figure 7 is an enlarged view of the line VII-VII of Figure 6, showing the location of the air ports for flowing decarbonizing air into the underfiring distribution system.

By appropriately moving reversing cable 61, fuel gas flowing through the gas main 50 is admitted by the reversing cock 51 into the riser pipe 52 and the distributor-header 53; through the latter, heating gas is carried cross-wise of the 70 75

battery and length-wise of each oven wall. Communicably connected for gas flow with header 53 are the gas pressure equalizing channels or ducts 54 that distribute, at uniform pressure to the 5 heating flues comprising each flue group, the fuel gas flowed to said channels from the distributor-header through the orifices 55. Interposed in the distribution system, between the orifices or valve means 55 and the pressure equalizers 54, are the 10 air boxes 56. Through these boxes, air may be drawn directly into the underfiring system by the stack suction during those intervals of the reversing cycle that no fuel gas is flowing into the flame flues of an oven wall through the reversing cock 51, and at such times as the air ports 57 of boxes 56 are opened to the battery basement atmosphere by raising the air port cover 58. The handles 59 of the port cover actuating mechanisms are attached to the rods 60, which are 20 disposed to open or close the covers 58 at such times as the reversing cock 51 has been respectively closed or opened to underfiring gas flow.

The height to which the air port covers are raised controls the quantity of air flowing into 25 the associated equalizing channels, and it is obvious that this improvement which permits the decarbonizing air to be flowed into rich gas conduits down-stream of the regulating orifices 55, not only facilitates the introduction of such air 30 into the underfiring system but also assures ample quantities thereof reaching the rich gas conduits unimpeded by line restrictions. Any air introduced into the pressure equalizers will be substantially equally distributed to all rich gas 35 conduits communicating therewith.

It is of obvious importance that a gas tight seal should be formed when the air port cover 58 closes the port 57, in order to prevent the escape of fuel gas into the battery basement.

40 My invention as hereinabove set forth is embodied in particular form and manner but may be variously embodied within the scope of the claims hereinafter made.

I claim:

45 1. In a coking retort oven battery, in combination: a plurality of side-by-side coking chambers; heating walls between and adjacent thereto and each comprising vertically disposed heating flues; cross-regenerators beneath the heating walls separated by division walls and adapted to communicate with the heating flues; conduits, in the regenerator division walls, for flowing unpreheated gas into the lower part of the heating flues, each such conduit passing downward 50 through the battery supporting mat to connect with a fuel gas distribution system located in passageways beneath said mat; accessible means for regulating the flow of heating gas from the distribution system therefor into the conduits within the regenerator walls; and means for introducing decarbonizing air into the regenerator wall conduits, said means being positioned in the fuel gas distribution system at points downstream of distributor-headers, said accessible 55 means for regulating the fuel gas flow to said conduits and heating flues being so disposed relative to the means for decarbonizing air that the decarbonizing air may be introduced into the conduits without restriction by the gas regulating means.

70 2. In a coking retort oven battery having vertically disposed flame heating-flues in heating walls that are arranged intermediately and laterally of coking chambers, the heating flues of 75 the walls being operatively disposed in individu-

ally regulable groups of flues for gas flow purposes, and regenerators for the flues of each heating wall separated from each other by division walls contiguous to regenerators adjacent each other, valveless individual conduits in the regenerator division walls for flowing rich gas individually to the respective flame flues from a rich gas distribution system therefor located in accessible passageways beneath the supporting mat of the battery, a bus channel individual to each flame flue group and each communicating with the valveless individual conduits for the flues of the group, a distribution system in the accessible passageway comprising at least one distributor header with conduit means comprising leader conduits each of which is individual and adapted to flow gas to but one group of the heating flue groups and communicably connected with the bus channel for the valveless conduits of the flues of the group for which the leader conduit is individualized, volume-control valve-means in the respective leader conduits for regulating the volume of gas flow therethrough to their respective bus-channels, and decarbonizing air-inlet valve-means for the respective leader conduits, the decarbonizing air-inlet-valve means for each leader conduit being communicably connected therewith between volume-control valve-means therefor and the bus-channel thereof.

3. In a coking retort oven battery, in combination: heating walls comprising vertical flame heating flues spaced intermediately of coking chambers, the heating walls tapering in such manner that the mass of coal to be coked per unit of wall area increases from one side to the other of the battery, and the heating flues, in the respective heating walls, being operatively disposed for gas flow in individually regulable groups along each half of each heating wall with the respective groups in each heating wall positioned similarly to the like groups in the other heating walls and groups in similar positions similar to each other, horizontal flow duct means communicably connecting the flues of each group with each other at their upper parts, and cross over flue means communicably connecting the horizontal flow duct means for each group of vertical flues in each heating wall with the horizontal flow duct means of a group of vertical flues similarly positioned in another heating wall, there being a cross over flue duct individual to the respective individual groups of flues cross-connected by the horizontal flow duct means and cross over flue means therefor, regenerators, separated by division walls, below the coking chambers and heating walls and communicably connected with the vertical heating flues thereof at their lower parts, individual rich gas supply conduits in said regenerator division walls individual to the vertical flues for individually supplying rich gas thereto at their lower parts, from a distribution system in an accessible passageway therefor below the battery supporting mat, a pressure equalizer channel for each of the flue groups, each equalizer channel being communicably connected with the rich gas supply conduits for its group of vertical flues and being individual thereto, a distribution system in the accessible passageway for distributing rich gas to the flue groups, said system comprising at least one distributor header provided with leader conduit means comprising leader conduits each of which is individual to a single one of the flue groups and communicably connects the equalizer chan-

nel of only its flue group with the distributor header, and an individual volume regulating means individual to each individual flue group, the individual volume regulating means for each group being located in the individual leader conduit that is individual to that flue group, for regulating the volume of flow from the distributor header to each of the respective flue groups individually.

4. A coke oven battery as claimed in claim 3, and in which separate distributor-headers are provided for each of the rows of groups of flues that are similarly positioned in the several heating walls, each separate distributor-header being individualized to only a single row of correspondingly positioned groups of flues in several heating walls for supply thereto of heating gas independently of the supply of other rows of groups in different positions in the heating wall.

5. A coke oven battery as claimed in claim 3, and in which a separate distributing header is provided for each heating wall extending substantially parallel therewith crosswise of the battery and each separate distributing header being individual to the groups of flues in a single heating wall only.

6. In a coking retort oven battery, in combination: heating walls comprising vertical flame heating flues spaced intermediately of coking chambers, the heating walls tapering in such manner that the mass of coal to be coked per unit of wall area increases from one side to the other of the battery, and the heating flues, in the respective heating walls, being operatively disposed for gas flow in groups along each half of each heating wall with the groups in each heating wall positioned similarly to those in the other heating walls and groups in similar positions similar to each other, horizontal flow duct means communicably connecting the flues of each group

with each other at their upper parts, and cross over flue means communicably connecting the horizontal flow duct means for each group of vertical flues in each heating wall with the horizontal flow duct means of a group of vertical flues similarly positioned in another heating wall, regenerators, separated by division walls, below the coking chambers and heating walls and communicably connected with the vertical heating flues thereof at their lower parts, individual rich gas supply conduits in said regenerator division walls individual to the vertical flues for individually supplying rich gas thereto at their lower parts, from a distribution system in an accessible passageway therefor below the battery supporting mat, a pressure equalizer channel for each of the flue groups, each equalizer channel being communicably connected with the rich gas supply conduits for its group of vertical flues and being individual thereto, a distribution system in the accessible passageway for distributing rich gas to the flue groups, said system comprising at least one distributor header provided with leader conduit means comprising leader conduits each of which is individual to one of the flue groups and communicably connects the equalizer channel of its flue group with the distributor header, and volume regulating means in each of the individual leader conduits for regulating the volume of flow from the distributor header to the respective flue groups individually, and in which the rich gas conduits are valveless conduits and in which a decarbonizing air valve is provided for each flue group, the decarbonizing air valves for each flue group being provided in the leader conduit therefor and located therein between the equalizer channel for the flue group and the volume-regulating means for the flue group.

JOSEPH BECKER. 40
